UNITED STATES PATENT OFFICE.

ARTHUR R. SPEER, OF PITTSBURG, PENNSYLVANIA.

PARTITION STRUCTURE.

No. 823,557.

Specification of Letters Patent.

Patented June 19, 1906.

Application filed February 6, 1905. Serial No. 244,493.

To all whom it may concern:

Be it known that I, ARTHUR R. SPEER, a citizen of the United States, residing at Pittsburgh, in the county of Allegheny and State of Pennsylvania, have invented certain new and useful Improvements in Partition Structures, of which the following is a specification, reference being had therein to the accompanying drawings, forming part of the specification, in which—

Figure 1 is a plan view of my improved partition construction for shipping cases, crates, &c. Fig. 2 is a partial section through a portion of one of the side or end walls, illustrating the manner of incorporating the terminals of the partition therewith. Fig. 3 is a detail plan view of one of the cross-joints, showing the manner of connecting the cross members together. Fig. 4 is a longitudinal section on the line IV IV of Fig. 3. Figs. 5 and 6 are similar views on the lines V V and VI VI, respectively, of Fig. 3. Fig. 7 is a detail perspective view of a portion of one of the cross members separated from the other member. Fig. 8 is a detail view illustrating a modification. Fig. 9 is a cross-section on the line IX IX of Fig. 8. Figs. 10 and 11 are sectional detail views showing different ways of securing the partitions to the case.

My invention refers to improvements in partition or separating structures for packing cases, boxes, crates, &c., and refers to the means for providing a stiff light device adapted for incorporation with a crate or box in such a manner as to divide it into a series of closely-adjacent spaces for the purpose of receiving and separating bottles or other similar articles.

The invention refers more particularly to the manner of constructing the partitions or racks of strips of light sheet metal bent into inverted-U form, secured together at each juncture by pressing the strips together, so as to provide a practically integral continuous rack, means also being provided whereby the rack may be readily and securely attached in position.

The device is particularly designed for incorporation with that class of sheet-metal packing or shipping cases for which I have filed an application for Letters Patent bearing the Serial No. 244,492, wherein two or more adjacent sections 2 of sheet metal forming the ends and sides are built up one upon another and connected by doubling the edge of one such section around a corresponding

flange 3 of the adjacent section, so as to provide outwardly-extending strengthening-ribs 4, which encircle the case and coincide with the joints. In this construction the racks 60 are conveniently attached by inserting their terminals 5 between such connecting portions, as shown in Figs. 1 and 2, and for such purpose I preferably employ racks made of strips of thin sheet metal adapted to be 65 formed with suitable flat terminals 5, as shown. The connecting-flanges of the sections being pressed together between each of such terminals 5 will firmly hold them against displacement. The body portion of the racks 70 between their terminals and the cross-joints are pressed into inverted-U form, as shown at 6, and at the points where the members cross each other at right angles, as shown in Fig. 1, they over and under lap each other 75 alternately. The strips are originally pressed out flat for a distance equal to the overlapping area of each member and are then secured together by the pressing action of a star-shaped or other form of die, producing a 80 corresponding depression or groove 7.

For the purpose of utilizing the stiffening action of such groove it preferably extends some distance beyond the side edges of each member, as shown in Fig. 3, thus producing a 85 cross-sectional shape of each member at each side of the side edges approximating an inverted W. If desired, the overlapping strips may be pressed together by a circular rounded die, providing a cup-shaped cavity 7', as 90 shown in Figs. 8 and 9, leaving a surrounding curved body portion in each strip. The members as thus pressed receive and retain an additional stiffness beyond the center of each cross-joint outwardly beyond the juncture of the edges of the members, while the pressing operation practically amalgamates the sections together, resulting in one continuous stiff rack of great strength. When this rack is incorporated with the case between 95 the sections or otherwise, it serves the further purpose of stiffening and bracing the walls at all points, so as to effectually overcome the distorting or bending strains to which articles of this class are subject in use. 100

In Fig. 10 I show one of the terminals 5 of the rack inserted between the connecting-flanges, which, with the terminals, are then indented or grooved, as at 8, while in Fig. 11 a holding-clip 9 is inserted between the sides 9 of strengthening-ribs of the case with which the terminal of the rack is connected, the parts then 105 110

being indented or grooved in a similar manner, thus firmly incorporating them together. The rounded upper surface of the partitions gives them a finished exterior. There are no 5 projecting points or edges. The joints are neatly rounded at the corners of each square aperture, while the device as a whole produces a finished efficient structure for the purpose desired. It is extremely strong, 10 very simple and cheap in construction, durable and effective in operation, and greatly adds to the efficiency of the case. While the manner of attachment with the case which I have shown and described has given good results in practice, it is obvious that it may be connected in any other suitable or desired manner or may be incorporated with a wooden case or with any other similar structure or vessel.

15 20 The device may be made of any size, proportions, or combinations, as desired, or may be variously changed in design or other details by the skilled mechanic; but all such changes are to be considered as within the scope of 25 the following claims.

What I claim is—

1. A partition structure consisting of a plurality of strips of sheet metal crossed at right angles to each other, flattened at the crossing 30 juncture and provided with cross-grooves pressed through both members, the intervening portion of the strips being bent into inverted-U form, substantially as set forth.
2. A partition structure consisting of a plurality of strips of sheet metal crossed at right angles to each other, flattened at the crossing juncture and provided with cross-grooves pressed through both members, the intervening 35 portion of the strips being bent into inverted-U form, and provided with flattened attaching-terminals, substantially as set forth.
3. The combination with a sheet-metal case formed of continuous jointed sections, 40 of a partition structure consisting of a plurality of strips of sheet metal crossed at right angles to each other, flattened at the crossing juncture and provided with cross-grooves 45 pressed through both members, the intervening portion of the strips being bent into inverted-U form; and provided with flattened

attaching-terminals inserted between the meeting portions of adjacent sections, substantially as set forth.

4. The combination with a sheet-metal 55 case having outwardly-extending strengthening-ribs formed of bent portions of the casting, of a partition structure having its terminals projecting between and embraced by the sides of said ribs, and means for securely 60 holding the terminals therein substantially as set forth.

5. The combination with a sheet-metal case formed of jointed sections, of a partition structure consisting of a plurality of cross- 65 strips, secured together, and provided with attaching-terminals inserted between the meeting portions of adjacent sections, and means for securely holding the terminals 70 therein substantially as set forth.

6. The combination with a sheet-metal case formed of jointed sections, of a partition structure consisting of a plurality of strips crossed at right angles to each other, secured together, and provided with attaching-terminals 75 inserted between the meeting portions of adjacent sections with means for securing the partition-terminals between the sections, substantially as set forth.

7. The combination with a sheet-metal 80 case formed of jointed sections, of a partition structure consisting of a plurality of strips crossed at right angles to each other, secured together, and provided with attaching-terminals inserted between the meeting portions of 85 adjacent sections, and held therein by securing-indentations, substantially as set forth.

8. The combination with a sheet-metal case formed of jointed sections connected together by folding the edge of one section 90 around an engaging flange in the adjacent section, of partition devices having their terminals extending between said meeting portions of the case, and means for securing the terminals in position, substantially as set 95 forth.

In testimony whereof I affix my signature in presence of two witnesses.

ARTHUR R. SPEER.
